HULL FOR SAIL-PROPELLED VEHICLE

Donald F. Rypinski, 2315½ Glenneyre,
Laguna Beach, Calif. 92651

Filed Mar. 21, 1968, Ser. No. 11,088

Term of patent 14 years

Int. Cl. D12—13

U.S. Cl. D14—3

FIG. 1 is a side elevation of a hull for sail-propelled vehicle embodying my new design;

FIG. 2 is a bottom view of the hull;

FIG. 3 is a top view of the hull;

FIG. 4 is a fragmentary front elevation of the hull; and

FIG. 5 is a fragmentary rear elevation of the hull.

The dominant features of my design reside in the portions shown in full lines, and the mast and sail are included for illustrative purposes only.

I claim:

The ornamental design for a hull for sail-propelled vehicle, substantially as shown and described.
